CHEMICAL FEEDING UNIT FOR SWIMMING POOLS

Thomas E. Schneider, Jr., 749 Woodward Way NW,
Atlanta, Ga. 30327

Filed Sept. 29, 1967, Ser. No. 8,794

Term of patent 14 years

(Cl. D23—3)

FIG. 1 is a perspective view of the chemical feeding unit for swimming pools showing one side and top of the device;

FIG. 2 is an elevational view of the chemical feeding unit for swimming pools, showing the side opposite from that shown in FIG. 1;

FIG. 3 is a top plan view of the chemical feeding unit for swimming pools; and

FIG. 4 is a bottom view of the chemical feeding unit for swimming pools.

The dominant features of my design reside in the portions shown in full lines.

I claim:

The ornamental design for a chemical feeding unit for swimming pools, as shown and described.
